UNITED STATES PATENT OFFICE.

PHILIP P. NUNGESESSER, OF CLEVELAND, OHIO, ASSIGNOR TO THE NUNGESESSER CARBON & BATTERY COMPANY, OF CLEVELAND, OHIO, A CORPORATION OF OHIO.

ELECTRICAL CONDUCTOR.

1,090,872.

Specification of Letters Patent. Patented Mar. 24, 1914.

Application filed December 5, 1913. Serial No. 804,803.

To all whom it may concern:

Be it known that I, PHILIP P. NUNGESESSER, a citizen of the United States, residing at Cleveland, in the county of Cuyahoga and State of Ohio, have invented certain new and useful Improvements in Electrical Conductors, of which the following is a specification.

This invention relates to electrical conductors, and more particularly to brushes for electric machines, the invention residing in the new and novel means for securing a flexible connection or conductor to the solid body of the brush, substantially as herein shown and described and more particularly pointed out in the claims.

In securing a flexible connection to the solid body of a brush, a good electrical bond is the first consideration. In the present invention such a bond is mechanically obtained by compressing the connection against the block. However, as the body of a brush of this kind is usually composed of carbon or copper and graphite or other friable or breakable material, the strains of compression must be carefully distributed, otherwise a large percentage of blocks will be split or broken and rendered absolutely useless. To eliminate this trouble and expense, I provide a very compact and simple form of screw fastener for the flexible connection which will distribute the strains of compression uniformly over a localized area and in parallel lines through the block; in brief, operating in effect in direct contra-distinction to tapered or wedge-shaped devices which impose cleavage strains upon the block.

In the accompanying drawing, Figure 1 is a perspective view of a brush embodying my invention. Fig. 2 is a sectional view of the block, and Fig. 3 a sectional and side view of the block with the flexible connection secured in place by my improved fastening device. Fig. 4 is a perspective view of the flexible connection showing a looped end. Fig. 5 is a perspective view of the concaved nut, and Fig. 6 a similar view of the screw.

The electrical conductor or brush comprises a solid body 2 of carbon, carbon and graphite, copper, or of any material or combination of materials possessing a high electrical conductivity and having self-lubricating properties. Body 2 is provided with a bore 4 transversely thereof near its upper

end to receive a clamping device consisting of a headed screw 5 and a round nut 6. The recesses or enlarged portions 7 and 8 of the bore 4 are relatively shallow but of unequal depth and of the same diameter, and both recesses have flat bottoms 9 in the same parallel plane relatively to one another and at right angles to the axis of the bore 3. The round flat head 10 of the screw is relatively thin and substantially equal in thickness to the depth of recess 7 in block 2, which brings the outside kerfed face of said head substantially flush with the side face of the block, and the bottom or inside face of head 10 is flat to correspond with the bottom of the recess.

The head 10 is relatively much larger in diameter than the threaded stem of the screw to provide a wide bearing surface corresponding with recess-bottom 9 in the brush body, and the round nut 6 is also relatively large in diameter to provide a wide seat for the loop 11 at the end of the flexible conductor 3. Loop 11 is dipped in solder or coated with an amalgam before placement in the bottom of recess 8, and the main portion of the connection extends through the inclined passage or opening 12 which opens into the bottom of recess 8 at one side of the smaller portion of bore 4. The inner face of nut 6 is particularly distinguished in that it is concaved or dished, and the concavity 14 is preferably circular and rounded, or in other words, it is an endless channel with a rounded surface and with its greatest depth centrally between the periphery of the nut and the central screw opening 15. The advantage of this formation of nut is, first, that the end or loop of the connection 3 is crowded to the center of the channel in the face of the nut and not spread outwardly against the annular wall of recess 8, and, second, the stock in the center of the nut is preserved for the greatest maximum number of threads in a nut of a given thickness, which at best is very small in brushes for small electric machines. Moreover, the concaved channel 14 localizes all the pressure upon the loop 11 in a circumscribed area at the bottom of the recess 8, the strains of compression upon the body 2 being in straight lines running parallel with the stem of the screw and the axis of bore 3 and within the radius encompassed or

defined by head 5 of the screw. Therefore, the connection 3 may be clamped or fastened to the solid body 2 under considerable pressure without splitting or breaking said body, 5 and the mechanical and electrical bond which is obtained is of the highest possible efficiency. The amount of stock in the block 2 between the nut and the head of the screw is also relatively large, very little material 10 being displaced, particularly as the recesses 7 and 8 are relatively shallow and the head 5 of the screw and the body of nut 6 are relatively thin. Nut 6 has a kerf or slot 17 for screw-driver engagement, and when the 15 parts are assembled and tightly fastened together with the outer faces of the screw head 5 and the nut 6 either flush or below the level of the sides of the body 2 the fastening may be made permanent by upsetting or center punching the end 18 of the screw stem.

What I claim is:

1. An electrical conductor, comprising a solid body, a flexible metallic connection, and a pair of clamping members to clamp said connection upon said body, one of said members having a concaved clamping face to engage said connection and localize the pressure in a circumscribed area of said body.
2. An electrical conductor, comprising a solid body, a flexible metallic connection, and a pair of clamping members comprising a screw and nut, one of said members having a circular channel to confine and compress said connection against said body.
3. An electrical conductor comprising a solid body having an opening for a clamping screw, a flexible connection, a clamping screw, and a nut having a clamping face 40 provided with a circular channel to seat said

flexible connection and center the strains of compression in the body about said screw.

4. An electrical conductor comprising a solid body having shallow side recesses and a communicating bore therebetween and 45 provided with a passage open to the bottom of one of said recesses, in combination with a flexible metallic conductor in said passage and a headed screw and nut in said recesses and bore, said nut having a channeled face 50 to seat the confined end of said connection.

5. An electrical conductor, comprising a solid body having intersecting passages therein, a flexible metallic connection extending through one of said passages and 55 having a looped end, a screw having a relatively large head seated within the other passage, and a nut having a central screw-threaded opening and a rounded channeled clamping face opposite said looped end of 60 said flexible connection.

6. An electrical conductor comprising a solid brush body having a cross passage and relatively shallow recesses at the respective ends of said passage, said recesses having 65 flat bottoms at right angles to the axis of said passage, and said body being provided with a second passage open to one of said recesses, in combination with a flexible metallic connection having a loop, a screw having a relatively thin head, and a nut for said screw having a rounded circular channel in 70 one face to seat said loop.

In testimony whereof I affix my signature in presence of two witnesses.

PHILIP P. NUNGESSER.
